EXTENSION TABLE

Edward G. Rudman, Nashua, and Francis G. Ranney, Hudson, N. H., assignors to Edward G. Rudman, Nashua, N. H., and Sidney S. Rudman, Brookline, Mass., copartners doing business as Old Colony Furniture Co.

Application October 8, 1937, Serial No. 167,882

3 Claims. (Cl. 311—41)

The invention relates to an improvement in extension tables.

Among the objects is:

To provide a table which, when unextended, will 5 show no evidence of its extensibility.

To provide a table which, when unextended, will present an unbroken top with drop leaves.

To provide a table capable of extension to the 10 right or left from a main top, or to both the right and left, and

To provide a table in which the main top, from 15 which the extension is made, will maintain its normal leg support when the table is extended and the extension will have its own leg support.

15 The invention can best be seen and understood in the light of the drawings in which—

Fig. 1 is a perspective of the table when unextended.

Fig. 2 is a perspective of the table when ex- 20 tended.

Fig. 3 is a top plan of the table extended with one of the top leaves removed and one of the drop leaves turned down.

Fig. 4 is a cross section on the line 4—4 of 25 Fig. 3.

Fig. 5 is a perspective of a portion of the table when extended showing especially its extensible parts.

Fig. 6 is a cross section on the line 6—6 of 30 Fig. 3.

Fig. 7 is a side elevation of a detail of construction, and

Fig. 8 is a side elevation of a fragmentary part 35 of the table when unextended.

In the table in its unextended form 1 represents its top; 2—2 side aprons; 3—3 end aprons; 4—4 drop leaves, and 5—5—5—5 supporting legs. Beneath the top spaced therefrom are table braces 6 connecting with the aprons 2—2. Interposed 40 between the braces 6 are brace blocks 7 all fixedly combined.

The top, side aprons, and legs are fixedly combined in any suitable manner and remain unchanged irrespective of any extension made to the 45 table. The end aprons 3—3 and drop leaves 4—4 are supported as will presently be explained from parts by which the table is extended, and these parts, when the table is unextended, lie concealed nested within a chamber, or housing, beneath the top which is formed by the top, side and end aprons.

The parts by which the table is extended comprise four sets of rail extensions 8, 9, 10 and 11 each comprising rails 12, 13, 14. Of these the 50 rails 12 are fixed and the rails 13, 14 extensible

in the usual manner. The sets of rail extensions 8 and 9 are arranged for extension to the right, and sets 10 and 11 to the left.

The rails 14 for all the sets of rail extensions 5 occupy the foremost positions when the rails are extended. Fixedly secured to the outer ends of these rails for the sets 8, 9; 10, 11, respectively are the end aprons 3—3 of the table. Each end apron is faced with drop leaf supporting blocks 16, 17 and 18 fixedly secured to the apron in any 10 suitable manner. Secured by hinged connections 19 to the top faces of these blocks for the respective aprons are the drop leaves 4—4 of the table.

When raised each of the drop leaves is supported to lie flush with the table top by hinged 15 brackets 20, of which there are preferably two brackets for each drop leaf. The brackets have hinge connection (of conventional type, not shown) with the blocks 16, 17, to which the respective leaves lie adjacent, the parts forming the 20 hinge connection between the brackets and blocks being connected by pintles 21. When folded, to permit the leaf to be dropped, the brackets fold in to lie, respectively, between the blocks 16 and 17 and the intermediate block 18, the brackets 25 and blocks then lying flush with one another.

When the table is extended each extension has its own leg support consisting of legs 24, 24¹. These legs are secured by hinge connections 25 to the respective rails 14, 14 of the extension to 30 occupy either operative, or out of the way positions, the leg 24 being secured to one rail, and the leg 24¹ to the companion rail. When moved to occupy operative positions they turn outwardly beneath the rails to project in vertical directions 35 downwardly therefrom with the top face 26 of each leg bearing against the bottom face of the rail from which it extends. At the same time a flange forming extension 27 at the top end of the leg will be brought to bear against the side of the 40 rail (see Fig. 6). This assists in localizing and giving firmness to the leg when extended. When moved to occupy their out of the way position the legs fold inwardly beneath the rails 14, 14 in crosswise relation thereto to lie boxed between the 45 end apron 3 of the extension and a brace bar 28 crossing the rails 14, 14 on the under sides thereof and fixedly secured thereto. When thus folded the legs lie parallel to one another with extension in reverse directions from the points at which 50 they are hinged.

The legs 24, 24¹ are held extended and braced each by a foldable brace 30. For the leg 24 one end of its brace is pivoted to the leg and the other end to the apron 3 of the table, the brace 55

folding with the leg to lie within a housing 31 within the apron. The brace for the leg 24¹ is pivoted at one end to the leg and the other end to the bar 28 within which is formed a housing 5 31¹ for the brace when folded with the leg.

When folded to lie boxed between the apron 3 and the bar 28 the legs 24, 24¹ are each held by a dished tip 32 on the end of the leg engaging a catch 33 carried by a block 34 fixed to the under 10 side of the rail to which the end of the folded leg lies adjacent. The folded legs may also be supported, if desired, by a button 32¹ pivoted to the bottom side of the bar 28.

When the table is unextended the rail extensions 8, 9; 10 and 11, the aprons 3-3, the legs 24, 24¹ and parts incidental thereto all lie concealed beneath the top 1 of the table which together with the aprons 2-2 and 3-3 provide a housing therefor. The drop leaves 4-4 will then 15 overhang the aprons 3-3 and when raised will coordinate with the edges of the table top to lie flush with the top. In this connection it will be seen by reference to Fig. 8 that with the table unextended the aprons 3 and blocks 16, 17 and 18 20 with which the aprons are faced will have entered 25 to lie between the permanent legs of the table, and the drop leaves 4 will occupy positions adjacent the formed edges of the table so that when the drop leaves are raised they will properly coordinate with these edges. This effect is obtained by the rail extensions 8, 9, 10 and 11 having 30 a limited inward movement as is customary in such extensions.

When the table is extended extension leaves 35 35 are laid over the extended rails and when raised the drop leaves coordinate with the edges of these inserted leaves to lie flush with the inserted leaves and table top.

To prevent lateral displacement the inserted 40 leaves 35 are preferably provided on their under sides with aprons 36 at either end thereof which overlap the ends of the aprons 3 with bearing against these ends.

We claim:

1. In an extension table the combination comprising a main section and an extensible section 45 slidably interconnected, said main section including an unbroken table top and stationary legs supporting said top, said extensible section 50 including extension rails normally nested within said table top and displaceable outwardly therefrom with determinate limits of extension and retraction, a drop leaf, means for mounting said drop leaf to lie supported from off the ends of the set of extension rails having the outermost extension when said extensible section is extended 55 in spaced relation thereto whereby the drop leaf will co-ordinate with said table top when said extensible section is in full retracted position, or with an inserted table leaf when said extensible section is extended, means for supporting said drop leaf when in its upturned position, foldable 60 legs for supporting said extensible section when extended, means for hingedly connecting said foldable legs to the outermost set of said extension rails to lie when folded beneath said rails with extension in opposing directions whereby said extension legs will ride upon said rails and be nested beneath said table top when said extensible section is in its full retracted position, or 65 said foldable legs occupy a vertical position supporting said extensible section when extended, a cross bar affixed to said rails with extension beneath the same normal thereto and cooperating with said apron to form a housing in which said 70 folding legs are contained when folded, means for holding said legs in place when folded, and means interposed between said legs and said apron and cross bar, respectively, assisting in the control of said foldable legs when in vertical 75 position supporting said extensible section as aforesaid.

obtain and maintain their respective folded and extended positions.

2. In an extension table the combination comprising a main section and an extensible section 5 slidably interconnected, said main section including an unbroken table top and stationary legs supporting said top, said extensible section including extension rails normally nested within said table top and displaceable outwardly therefrom with determinate limits of extension and 10 retraction, an apron affixed to the ends of the set of extension rails having the outermost extension when said extensible section is extended, spaced blocks affixed to said apron, a drop leaf, means for hingedly supporting said drop leaf to said 15 blocks from off said apron to occupy a position spaced from said apron when said leaf is dropped, a bracket hinged to one of said blocks and normally located within the space between said drop leaf and apron and movable therefrom to support said leaf when the leaf is in a horizontal raised position, foldable legs for supporting said extensible section when extended, means for hingedly connecting said foldable legs to the outermost set of said extension rails to lie when 20 folded beneath said rails with extension in opposing directions whereby said extension legs will ride upon said rails and be nested beneath said table top when said extensible section is in its full retracted position, or said foldable legs occupy 25 a vertical position supporting said extensible section when extended, and means for controlling said foldable legs to obtain and maintain their respective folded and extended positions.

3. In an extension table the combination comprising a main section and an extensible section 35 slidably interconnected, said main section including an unbroken table top and stationary legs supporting said top, said extensible section including extension rails normally nested within 40 said table top and displaceable outwardly therefrom with determinate limits of extension and retraction, a drop leaf, means for mounting said drop leaf to lie supported from off the ends of the set of extension rails having the outermost extension when said extensible section is extended 45 in spaced relation thereto whereby the drop leaf will co-ordinate with said table top when said extensible section is in full retracted position, or with an inserted table leaf when said extensible section is extended, means for supporting said drop leaf when in its upturned position, foldable 50 legs for supporting said extensible section when extended, means for hingedly connecting said foldable legs to the outermost set of said extension rails to lie when folded beneath said rails with extension in opposing directions whereby said extension legs will ride upon said rails and be nested beneath said table top when said extensible section is in its full retracted position, or 55 said foldable legs occupy a vertical position supporting said extensible section when extended, a cross bar affixed to said rails with extension beneath the same normal thereto and cooperating with said apron to form a housing in which said 60 folding legs are contained when folded, means for holding said legs in place when folded, and means interposed between said legs and said apron and cross bar, respectively, assisting in the control of said foldable legs when in vertical 65 position supporting said extensible section as aforesaid.
